DESIGN FOR A COAT

Max L. Romer, New York, N. Y.

Application September 9, 1938, Serial No. 79,805

Term of patent 3½ years

To all whom it may concern:

Be it known that I, Max L. Romer, a citizen of the United States of America, residing in New York city, in the Borough of Manhattan, county and State of New York, have invented a new, original, and ornamental Design for a Coat, of which the following is a specification, reference being had to the accompanying drawing, forming part thereof, wherein

The characteristic feature of my design resides in the specific combination of the buttons and fur trimming on the sleeves of the specific coat as shown.

I claim:

The ornamental design for a coat, substantially as shown and described.

MAX L. ROMER.
